A. W. Overbaugh,

Making Buttons.

No. 56,791.

Patented July 31, 1866.

Witnesses;

Gilbert Sting

Inventor,

William H. Motteup Abraham W. Overbaugh

UNITED STATES PATENT OFFICE.

ABRAHAM W. OVERBAUGH, OF NEW YORK, N. Y.

IMPROVEMENT IN INITIAL STUDS.

Specification forming part of Letters Patent No. **56,791**, dated July 31, 1866.

To all whom it may concern:

Be it known that I, ABRAHAM W. OVERBAUGH, of New York, in the county of New York and State of New York, have invented a new and Improved Mode of Manufacturing Initial Jewelry or Ornaments; and I do hereby declare that the following is a full and exact description thereof, reference being had to the accompanying drawings, and to the letters of reference marked thereon.

The nature of my invention consists in a separate initial plate, as shown in Figure C. This plate can be inserted or changed at pleasure and fastened into a rim, as shown in Fig. D, by reason of a plate attached to the shank of button, as shown by Plate E.

Figure A is a perspective view of a sleeve-button. Fig. B is a front view. Fig. C is an initial plate. Fig. D is a back view of rim. Fig. E is a side view of shank of button, to which is attached fastening for initial plate. Fig. F is a front view of same.

What I claim as my invention, and desire to secure by Letters Patent, is—

The application of the changeable initial plate in the manufacture of buttons, pins, earrings, and other jewelry or ornaments generally, as hereinabove described.

ABRAHAM W. OVERBAUGH.

Witnesses:

GILBERT S. KING,
WM. NORTHRUP.
